UNITED STATES PATENT OFFICE.

RALPH S. POWER, OF CLIFTONDALE, MASSACHUSETTS.

SKIVING-MACHINE.

1,162,395.

Specification of Letters Patent. Patented Nov. 30, 1915.

Application filed May 21, 1915. Serial No. 29,688.

To all whom it may concern:

Be it known that I, RALPH S. POWER, citizen of the United States, residing at Clifftondale, county of Essex, State of Massachusetts, have invented a certain new and useful Improvement in Skiving-Machines, of which the following is a specification, reference being had therein to the accompanying drawings.

My invention has for its object the production of a new and improved form of presser foot for use in connection with leather skiving machines.

The device embodying my invention is arranged to coöperate with a feed roll and feed disk of well known form to cause leather to be fed to a rotary knife or other cutting mechanism in such a manner that the proper scarf is made on the leather.

Heretofore great difficulty has been experienced in obtaining a scarf of even width and thickness owing to the inability of the presser foot to hold the leather firmly in position under all conditions. The presser foot now in commercial use is provided with a rigid head of metal which is integral with a yielding member upon which it is mounted. The rigid presser head bears against that portion of the leather to be skived and holds it in position when fed to the cutter. If the leather is smooth and of uniform thickness transversely of the scarf to be cut the presser foot as now constructed does its work relatively satisfactorily; but if a lump in the leather is encountered the presser foot is lifted and that portion of the leather to be skived at the sides of the lump is relieved of the pressure and consequently tends to spring up. When the leather has sprung up a wider and deeper scarf is made at this point which often results in nicking the edge of the blank.

It is also frequently desirable to skive again a blank upon which a scarf has already been formed, as for instance when the operator has not set the presser foot to produce the desired thickness of edge. Heretofore it has not been possible to do this and it has been customary to throw away a blank the edge of which is not thin enough because if an attempt is made to skive it again to reduce its edge to proper thickness it will be nicked and rendered useless. This has resulted in a considerable loss of stock.

The machine embodying my invention

makes it possible to skive again a piece which has already been skived bringing the edge to proper thickness and making a perfectly good smooth scarf. Furthermore it is often necessary to run a skive across one previously made as where there is a sharp angle in the edge of the piece to be skived at which time the presser foot must travel over a surface having a different inclination from that at which the surface of the presser foot is set at. This results in nicking or cutting off the corner of the leather and destroying the blank.

The device embodying my invention is simple and inexpensive to produce and is capable of being applied to skiving machines of various kinds already in use.

In the accompanying drawings I have shown my device as applied to a skiving machine of the disk knife type, commonly known as an Amazeen machine, but it will be understood that I do not limit myself by so doing since the device may be used with equal success with the machines of the cylindrical knife type.

My invention will be fully understood from the following description when taken in connection with the accompanying drawings and the novel features thereof will be pointed out and clearly defined in the claims at the close of the specification.

In the drawings Figure 1 is a front elevation of the feeding and cutting mechanism of a skiving machine, the same being provided with a presser foot embodying my invention. Fig. 2 is a plan view of a gage provided with a device embodying my invention shown in position over a feed roll. Fig. 3 is an end view of the parts shown in Fig. 2. Fig. 4 is a section of a portion of an already skived piece of leather showing the presser member in cross section. Fig. 5 is a plan view of a portion of a gage provided with a modified form of presser member.

Having reference to the drawings and particularly to Fig. 1 there is shown the feeding mechanism of a skiving machine of the type now commonly in commercial use. This consists of a feed roll 11 which is mounted on a shaft 12 journaled in the bracket 13 which is secured to the frame of the machine not shown. The feed roll 11 has a feeding surface 14 which is beveled as shown and a surface 15 which is separated from the feed-

ing surface 14 by a shoulder 16 adapted to coöperate with the edge of a suitable feed disk 17. The feed disk 17 is provided with a hub 18 and is mounted on a shaft 19 which is journaled in a supporting member 20 and is rotated by a belt actuated pulley 21 secured at its upper end. The shaft 12 is in like manner adapted to be rotated by any suitable mechanism not shown, both shafts 10 being arranged so that the edge of the feed disk 17 moves in the same direction and at the same rate with the shoulder 16 of the feed roll 11. A suitable cutter 22, which is preferably of the disk type as shown, but 15 may be of any other well known form is mounted closely adjacent the feed roll and feed disk on a shaft 23 which is journaled in the supporting member 24 and is provided with a belt actuated pulley 25. The presser 20 foot, which holds the leather 26 yieldingly against the feed roll and in the proper position while being fed to the cutter 22 by the feed roll and feed disk, is mounted on a gage 27 secured to a supporting member 28 fast 25 on the frame of the machine. The gage is provided with the usual gage member 30 which is curved to fit the periphery of the feed roll 11 and with a slot 29 which is adapted to receive the shank of a machine 30 screw 30 with which the supporting member 28 is provided thereby enabling the gage to be adjusted longitudinally of the axis of the feed roll in a manner well known to those skilled in the art. On the upper side 35 of the gage 27 a flat spring metal member 31 is secured by means of a screw 32 at one end of the member 31. A slightly elongated slot 33 in the member 31 is adapted to receive a pin 34 with which the gage 27 is 40 provided which enables the member 31 to be sprung upwardly but prevents it from being moved about the screw 32 as a pivot. A thumb screw 35 passes through the member 31 and contacts with the gage 27. By 45 this construction it will be seen that the spring member 31 may be adjusted with relation to the feed roll 11.

The free end of the bar 31 is provided with a rib 36 which projects out over the feed roll. On the rib 36 the presser member 37 is located. It consists of a thin piece of tempered steel 38 which is conveniently secured to the rib 36 by being bent around as shown in Fig. 3 and held in position by 50 screws 39. The front part 40 of the member 38 is sufficiently thin so that it is capable of springing readily under pressure and in my preferred form consists of a plurality of blades or fingers 41 which are separated by 55 slots all as shown in Fig. 2. The blades 41 which are of thin metal as stated, are held down against the leather 26 with a firm pressure by the spring member or bar 31. Where there is a lump or an unevenness in 60 the leather the blade or blades which come

directly in contact with said unevenness yield against the pressure of the member 31 allowing the uneven spot to pass without lifting the other blades from out of contact with the leather.

It will be understood of course that the pressure on a part of the blades such for instance as is produced by a bunch in the leather or by a piece which has already been skived is sufficient to overcome the resistance of such of the blades as are in contact with the bunch or ridge in the leather, but is not sufficient to overcome the resistance of spring member 31; on the contrary the united resistance exerted by all of the 75 blades will be sufficient to overcome the resistance of the spring member 31 and lift it up. The result is that part of the blades will rise to permit the passage of the hump or thick spot while the remainder of the 80 blades continue to exert a uniform pressure on the remainder of the leather as it passes through the machine.

At 61 in Fig. 2 is shown a curved backing member which is preferably formed integral with the rib 36 against which the inner blades rest. It will be seen that the effective length of the blades is thereby progressively reduced toward the edge of the piece of leather to be skived, that is, toward the right 90 as seen in Fig. 2, and that consequently a greater pressure will be required to cause the inner blade to move than the one next to it, the resistance of these spring blades being substantially inversely proportional 95 to their effective length. This offers the greatest resistance along the edge of the piece which is the point at which it is most desirable to have the work held firmly in position.

In Fig. 4 I have shown the position of the blades 41 on the leather when a portion of the leather upon which the presser member rests has been previously skived. It will be noted from this figure that the upper surface of the scarf 50 is at an angle to the lower surface. The pressure surface of the presser member is necessarily set parallel with the feeding surface of the feed roll 11 as is clearly shown in Fig. 1, and therefore 110 is at an angle to the upper surface of the scarf. It will be seen from this figure that the blades not only yield upwardly individually but also twist slightly, their tendency being to lie flat against whatever surface they are in contact with regardless of its 115 angle of inclination.

In Fig. 5 there is shown a modified form of presser member which consists of a thin spring metal blade 53 which is secured to the member 31 in the same manner as the presser member described above. The blade is not divided into smaller blades as the preferred form of presser member but nevertheless is sufficiently thin to yield irregu- 120 125 130

larly to take care of the hard spots, skived portions, etc., in the leather. While the other form of presser member is to be preferred, in many instances, I find this member is entirely satisfactory. My device has the further advantage that the operator may more readily guide the leather through the feeding mechanism to the knife. In all presser feet heretofore constructed so far as known to me, it is impossible for the operator to see the chip which is cut by the knife until one-quarter of an inch or more of it has been cut. The presser foot is necessarily located in a position where it is under other parts of the skiving machine. The operator therefore cannot look directly down upon the presser foot but must look at it from an angle in front of the machine. In the solid presser members employed the edge of the knife at the time of the cutting is concealed from the front of the machine owing to the thickness of the presser member which completely covers up the point of cut and also prevents a portion of the chip from being seen. The operator must guide the leather by the thickness of the chip and where he cannot see the chip as it is cut the mistake in the guiding may produce a perceptible error in the skiving before he is aware of the fact and can correct the mistake. The device embodying my invention is so arranged that the operator can see the chip at the cutting point without getting his head into the machine and can rectify mistakes in the guiding as soon as they are made so that no perceptible variation in the skiving will result.

What I claim is:

1. In a leather skiving machine the combination of a rotary knife, a feed wheel having a beveled feeding surface adapted to cooperate with said knife, a supporting member adjacent said feed wheel and rotary knife, and a presser member secured to said supporting member, said presser member comprising a thin spring metal blade having an effective surface substantially parallel with the bevel on said feed wheel.

2. The improved presser foot for skiving machines comprising a yielding supporting member, and a presser member secured to said supporting member, said presser member having a thin spring metal blade.

3. In a leather skiving machine the combination of a rotary knife, a feed wheel having a beveled feeding surface adapted to cooperate with said knife, a supporting member adjacent said feed wheel and rotary knife, and a presser member secured to said supporting member having an effective surface composed of a series of thin spring metal blades.

4. The improved presser foot for skiving machines, comprising a yielding supporting member, and a presser member secured to

said supporting member, said presser member having an effective surface composed of a series of thin spring metal blades.

5. A presser foot for skiving machines comprising a supporting member, and a presser member secured to said supporting member consisting of a curved sheet of spring metal, a portion of said sheet of spring metal having slots therein to form a plurality of spring blades.

6. In a leather skiving machine the combination with a leather feeding member and a knife, of a presser foot, said presser foot consisting of a yielding supporting member and a presser member, said presser member having an effective surface which is under an elastic pressure independently of said yielding supporting member and adapted to hold leather against the said feeding member in advance of the knife.

7. In a leather skiving machine the combination with a leather feeding member and a knife, of a presser foot, said presser foot consisting of a yielding supporting member and a presser member, said presser member having an effective surface capable of yielding throughout independently of said supporting member and adapted to hold leather against the said feeding member in advance of the knife.

8. The improved presser foot for skiving machines comprising a supporting member, a presser member secured to said supporting member, said presser member comprising a thin spring metal blade, and a reinforcing member adjacent to and overlying a portion only of the upper surface of said thin metal blade, whereby the pressure exerted by said portion of the spring metal blade is greater than that exerted by the remaining portion of said blade.

9. The improved presser foot comprising a yielding support, a rib on said support projecting from one end thereof, and a presser member detachably secured to said rib, said presser member being curved around said rib and having an effective portion adapted to contact with leather, said effective portion consisting of a plurality of spring metal blades.

10. The improved presser foot for skiving machines comprising a supporting member, a presser member secured to said supporting member, said presser member having a thin spring metal blade, and a reinforcing member in contact with the upper surface of said thin metal blade for an area which is greater near the supporting member whereby the pressure exerted by the portion of the spring blade near the supporting member is greater than that exerted by the portion thereof which is farther away from said supporting member.

11. The improved presser foot for skiving machines consisting of a yielding support

- ing member, and a presser member secured to said supporting member having a yielding pressure surface, the elasticity of said yielding supporting member and of said yielding pressure surface being so proportioned that when greater pressure is exerted over one portion of the area of said pressure surface than over the remaining portion, said portion will yield before said supporting member yields, and when pressure is exerted over substantially the entire area of said pressure surface said supporting member will yield substantially at the same time with said presser member.
12. In a leather skiving machine the combination of a rotary knife, a feed wheel adjacent the said rotary knife and adapted to coöperate therewith, a supporting member adjacent said feed wheel and rotary knife, and a presser member secured to said sup-

porting member comprising a thin metal blade, said thin metal blade being secured to said supporting member at a point nearer to the operator than the edge of said metal blade whereby the operator has an unobstructed vision of the edge of the blade. 25

13. In a leather skiving machine the combination of a rotary knife, a feed wheel having a feeding surface adjacent the said rotary knife and adapted to coöperate therewith, a supporting member adjacent said feed wheel and rotary knife, and a presser member secured to said supporting member, said presser member comprising a thin spring metal blade having an effective surface substantially parallel with the feeding surface of said feed wheel. 30 35

In testimony whereof I affix my signature.

RALPH S. POWER.
